INVENTOR

Ture Gustaf Rennerfelt

UNITED STATES PATENT OFFICE.

TURE GUSTAF BENNERFELT, OF NEW YORK, N. Y.

METHOD OF ANNEALING AND APPARATUS THEREFOR.

Application filed December 29, 1922. Serial No. 209,658.

To all whom it may concern:

Be it known that I, TURE GUSTAF BENNERFELT, citizen of the Kingdom of Sweden, and resident of New York city, in the county of New York and State of New York, have invented certain new and useful Improvements in Methods of Annealing and Apparatus Therefor, of which the following is a specification.

10 My invention relates to improvements in furnaces for heating, or for annealing metals, for instance steel. My improved furnace is particularly adapted for annealing cold rolled steel, heating it gradually to a red heat and permitting it to cool slowly, so that the steel will lose the hardness acquired by the cold rolling process, and so that it will retain its bright and spotless surface. To gain this purpose my invention 15 comprises means and apparatus to entirely prevent access of air or oxygen to the hot metal, and it is directed also to a new method of operating an annealing furnace for such purpose.

20 My invention is illustrated in the accompanying drawing, in which Fig. 1 shows a vertical section of my improved furnace, Fig. 2 shows a cross section of the furnace, taken on line X—X of Fig. 1.

25 Referring to the drawing, 2 represents a muffle or crucible arranged to contain the objects to be heated, and made of refractory material or, as shown on the drawing, of iron and thus able to withstand the shocks which will occur when the objects are sunk into or lifted from the muffle. The top of the muffle is open, otherwise the muffle is airtight. 3 represents a lid fastened to the top of the muffle, a packing, for instance of asbestos, being interposed to make the joint fairly tight between lid and muffle. 4 represents a pipe leading from the bottom of the muffle, 5 another pipe leading from the top, and 6 a small hole in the lid, closed by a screw. 7 represents a brickwall built around the muffle and formed with an air space 8. The heat is generated in the annular space between the wall and the muffle either by burning of gas, or as shown in the drawing, by electric means. Three tubes 9, 9, 9 made of refractory material and containing pieces of coke 10 are arranged around the muffle, the coke filling extending through the wall at 11, forming terminals for connection to a 3-phase electric power circuit. 12, 12 represent openings at the bottom

of the tubes, through which openings the coke fillings in the three tubes are electrically connected together. When the electric current is applied to the terminals 11 it will flow through the coke fillings so as to generate heat which is radiated to the muffle and its contents. 14 represents a window through which the glowing muffle may be observed. 15, 15 represent lids covering openings to the airspace and arranged to be opened more or less so as to regulate the cooling of the furnace. 16 represents a removable roof resting on the wall. 17 represents a closed tank located at a lower level than the muffle, arranged to contain kerosene, or other suitable liquid and connected with the muffle through the pipe 4. In this pipe connection 4 is a valve 18, a gage 19 and the centrifugal pump 20 arranged to pump liquid from the tank into the muffle. 21 represents a tank or reservoir containing carbonic acid or other neutral gas and connected with the muffle through the pipe 5 for the purpose of filling the muffle with gas at a pressure slightly greater than atmospheric pressure. 22 represents a reducing valve which may be placed in the pipe connection 5 for regulating the pressure. 23 represents a valve, 24 a cooling device and 25 a vessel containing a liquid hydrocarbon. 26 is a bent pipe of which one end extends into the vessel 25, its other end being connected to the pipe 5. A valve 27 is located in the pipe 26.

30 The method of operating the above described furnace is as follows: The roof 16 and the lid 3 being removed, the objects to be annealed are lowered into muffle for instance by means of chains. The objects may consist of steel bars or steel strips formed into coils or may be of some other shape. The lid 3 is placed on the muffle and tightened, the roof 16 is put in place and valve 27 opened—the valve 23 being closed beforehand. The valve 18 is opened and the pump started so that the liquid is drawn from the tank 17, creating a vacuum therein, and forced into the muffle so that most of the air contained within the muffle is driven out through pipes 5 and 26. When the liquid flows into the vessel 25, the valve 27 is closed. For removing the remainder of the air from the muffle the pump is stopped, so that the liquid flows back to the tank 17, thereby creating a vacuum in the muffle. This will cause such air as may be confined

in crevices between the objects to expand and be dislodged by vapors from the liquid. The pump is now started again so that the muffle is completely filled with the liquid; 5 the amount of air above the pipe 5 which was not driven out through the pipe 26 is allowed to escape through the hole 6 by loosening the screw which keeps it normally closed. The screw is now tightened, the 10 valve 18 is closed and the pump stopped. The valve 27 is now opened, a hydrocarbon heavier than kerosene is poured into the vessel 25, and the valve 23 is opened. Then the valve 18 is opened so that the neutral 15 gas will drive the liquid from pipes 26 and 5 and from the muffle back into the tank 17. When the gage 19 indicates that the pipe 4 is emptied from liquid the valve 18 is closed. The space within the muffle, which is not 20 occupied by the metal objects, is now filled with a neutral gas at slightly greater than atmospheric pressure. The hydraulic seal formed by the oil in the vessel 25 prevents the gas from escaping through the pipe 26, 25 and the loss of gas caused by leakage around the edge of the lid 3 is small by reason of the small difference in pressure. Water is now turned on to the cooling device 24, and the heating of the furnace begins, by gas or 30 electricity or coal, so that the muffle with its contents is slowly brought to a red heat. During this heating period the gas within the muffle will expand so that about two thirds of the weight of the gas will escape 35 through the liquid seal in 25. The temperature may be watched by means of pyrometers placed inside of the wall or by observing the muffle through the window 14. When the muffle is sufficiently heated, the 40 firing of the furnace is stopped, and it is allowed to cool slowly. During the cooling period the same amount of gas which escaped during the heating must be returned to the muffle. This amount is automatically 45 supplied from the tank 21 and through the reducing valve 22, no part of it coming through the pipe 26 by reason of the liquid seal 25. The cooling of the furnace may be to some extent regulated by the lids 15, 15. 50 When the furnace is sufficiently cold the roof and the lid 3 are removed, the valve 23 is closed, and the objects lifted out of the muffle. They are now annealed, and since they were protected, while hot, from contact 55 with any gas that could affect them their original bright and spotless surface will be retained.

Many modifications can be made in the above described apparatus and still fall 60 within the scope of my claims. Some other liquid than kerosene can be used, for instance, gasoline, alcohol or ether. I can also use some other neutral gas than carbonic acid, for instance, nitrogen or common illuminating gas. The hole 6 in the lid may

be omitted, and the amount of air remaining in the muffle above the pipe 5 can be washed out by lowering the surface of the liquid in the muffle, injecting gas from the pipe 5 and driving out the mixed gases by 70 again raising the level of the liquid. The muffle may be made of rustfree steel, or it may be constructed of refractory material or formed integrally with the tubes 9 or with some parts thereof. 75

Having thus described my invention, what I claim is:

1. The method of annealing steel which consists in heating and cooling the steel while it is surrounded by a neutral gas at 80 a pressure higher than atmospheric pressure, opening an exit into the atmosphere for a part of the gas during the heating period, closing the exit and supplying an additional amount of gas during the cooling period. 85

2. The method of annealing steel within a muffle, which consists in placing the steel in the muffle, filling the muffle with a liquid, replacing the liquid by a neutral gas, heating 90 the muffle and allowing it to cool.

3. The combination of a muffle arranged to contain metal objects, means for filling it with a liquid, means for replacing the liquid by a gas, and means for heating the 95 muffle. 100

4. The combination of a muffle arranged to be heated, means for filling it with a liquid, and means for replacing the liquid by a neutral gas at a pressure greater than 100 atmospheric pressure. 105

5. The combination of a muffle, a tank at a lower level than the muffle arranged to contain a liquid, a pipe connection from the bottom of the muffle to the tank, a pump in the pipe connection, a reservoir arranged to contain a neutral gas, a pipe connection between the muffle and the reservoir, and means for heating the muffle. 110

6. The combination of a muffle for annealing steel, means for removing air from the muffle, means for filling it with a neutral gas at greater than atmospheric pressure, and means for heating the muffle, together with means for causing a part of the gas to escape into the atmosphere during the heating period, means for cooling the muffle, and means for supplying gas to the muffle during the cooling period. 115

7. The combination of a muffle arranged to contain metal objects, means for creating a vacuum in the muffle, means for filling it with a gas, and means for heating it, together with automatically operating means for opening an exit into the atmosphere for a part of the gas during the heating period. 120

8. The combination of a muffle arranged to contain metal objects, a tank arranged to contain a liquid, a pipe connection between 125

- the muffle and the tank, a reservoir arranged to contain a neutral gas, a pipe connection between the muffle and the reservoir, a vessel, and a branch pipe extending from 5 the last said pipe connection into the vessel.
9. The combination of a muffle arranged to contain metal objects, a tank arranged to contain a liquid, means for forcing liquid from the tank into the muffle, means 10 for drawing the liquid from the muffle into the tank, a reservoir arranged to contain a neutral gas, a pipe connection between the muffle and the reservoir, and a reducing valve in the pipe connection.
10. The combination of a muffle, means 15 for creating a vacuum therein, a reservoir arranged to contain a gas, a pipe connection between the muffle and the reservoir, and a reducing valve in the pipe connection.
11. The combination of a muffle, means 20 for creating a vacuum therein, a reservoir arranged to contain a gas, a pipe connection between the muffle and the reservoir, a vessel, and a branch pipe extending from 25 the pipe connection into the vessel so as to form a seal.
12. The combination of a muffle, means 30 for filling it with a neutral gas, a vessel arranged to contain a liquid, a pipe connection between the muffle and the vessel, and means for heating the muffle.
13. The combination of a muffle, means
- for creating a vacuum therein, means for filling it with a neutral gas, a vessel arranged to contain a liquid, a pipe extending 35 from the muffle into the vessel, means for heating the muffle, and means for cooling the pipe.
14. The combination of a muffle, means 40 for filling it with a neutral gas, a vessel arranged to contain a liquid and to form a liquid seal, a pipe connection between the muffle and the said seal, means for heating the muffle, and means for cooling the pipe connection.
15. The method of annealing metal with- 45 in a muffle which consists in placing the metal in the muffle, creating a vacuum in the muffle, filling it with a neutral gas, heating the muffle and allowing it to cool.
16. The method of annealing metal with- 50 in a muffle which consists in placing the metal in the muffle, creating a vacuum in the muffle, filling it with a neutral gas, heating the muffle and expelling a part of 55 the gas therefrom, cooling the muffle and supplying an amount of gas thereto.

Signed at New York city, in the county of New York and State of New York, this 28th day of December, A. D. 1922.

TURE GUSTAF RENNERFELT.
